TRAJAN VUIA, OF GARCHES, FRANCE.

PROPELLING, TRACTIVE, AND SUPPORTING APPARATUS.

1,347,424.

Specification of Letters Patent. Patented July 20, 1920.

Application filed March 4, 1919. Serial No. 280,678.

To all whom it may concern:

Be it known that I, TRAJAN VUIA, a subject of the King of Roumania, residing at Garches, Seine-et-Oise, France, have invented certain new and useful Improvements in Propelling, Tractive, and Supporting Apparatus, of which the following is a specification.

This invention consists in improvements having for their object to increase the efficiency of tractive, propelling and supporting apparatus, such as the propellers of flying machines, ships, and the blade wheels of turbines.

For the purpose of increasing the efficiency of propelling and tractive means, it has been proposed, apart from effecting an increase in the diameter and diminishing the speed of rotation, to increase the number of the blades, the pitch of the screw propellers and also to arrange a plurality of propellers one above another on the same axis. Of all the proposed means none has come into practical use.

In making experiments for the purpose of determining the conditions of the working and efficiency of screw propellers, attention has been paid only to the ratio of the work to the tractive force or to the supported load. In this manner the following law has been established:

"When the speed of rotation increases, the tractive force increases as the square, and the work as the cube of the speed".

In order to determine the tractive or supporting effect of screw propellers, a distinction must be made between the function of a screw propeller when it is intended to draw a small load at a high speed (pulling or pushing screw propeller) and the function of a screw propeller intended to draw a great load at a low speed (supporting screw propeller).

On the other hand it is the wing load which is the criterion for determining the load supported per unit of power.

It may thus be said that all inclined planes subjected to rotary motion support per unit of power a load which is the greater the smaller the wing load per unit of carrying surface.

The law above referred to must be completed as follows:

"The load supported per unit of power is in inverse proportion to the velocity of ro-

tation or to the wing load per unit of carrying surface.

The supported weight and the wing load per unit of carrying surface increases as the square of the velocity of rotation. The work consumed increases as the cube of said velocity."

The improvement forming the subject matter of the present invention consists in the combination upon one shaft of two propellers or inclined planes and the like having different pitches such that the incidence or pitch of the propeller or inclined plane on the exit or exhaust side is 75% greater than the incidence or pitch of the propeller on the suction or admission side.

This improvement is general and applies also to screw propellers proper, that is to say, for pushing or pulling purposes, working in air or in water, and also to rotary inclined planes as well as to blades of turbines.

The efficiency will be increased only when, according to the present invention, the incidence of the upper blades is appreciably less than that of the lower blades. This increase is the greater the smaller the wing load per unit of carrying surface, that is to say, the screw propellers become supporting propellers.

It is to be noted that the same phenomenon occurs also when the screw propellers or rotary planes revolve in the same direction as well as when they revolve in opposite directions relatively to one another.

Referring now to the accompanying drawings which illustrate the invention as applied to screw propellers:

Figure 1 is a view looking at right angles to the axis and showing the length of the blades,

Fig. 2 is an end view of Fig. 1, and

Fig. 3 is a plan of Fig. 1.

The reference letter *a* indicates a suitable shaft upon which the propellers are mounted. In the form illustrated two propellers *b* and *c* are shown, the propeller *b*, as before mentioned, having the lower incidence and being arranged on the suction or admission side, while the propeller *c* has the higher incidence and is disposed on the exit or exhaust side. It has been found by experiment that, if for example the upper blade or plane has an incidence of eight degrees, then the lower blade of plane should have an in-

cidence of fourteen degrees, in other words, the pitch of the lower propeller will be 75% higher than that of the upper propeller in order to obtain the greatest degree of efficiency.

- The efficiency of this arrangement is greater when the superposed blades or planes are staggered relatively to one another in such a manner that the blade or plane having the smallest pitch or smallest incidence is located in advance of the blade or plane having the greater pitch or incidence. According to the present invention the blade having an incidence of 8° is located in advance of the blade having an incidence of 14° by a distance equal to the width of the blade.

The illustrated embodiment of the invention shows the screw propellers superposed above one another on a vertical axis, but it is to be understood that the reasoning and the improvement set forth hereinbefore are applicable irrespectively of the position of the axis of the screw propellers or rotating wings.

It is also to be understood that the wing surfaces hereinbefore referred to are actual wing surfaces and not surfaces resulting from the projection of the blades or planes upon a plane at right angles to the axis of the system, and also not to a circle swept by the blades or planes.

It is to be noted that the phenomena hereinbefore set forth are produced equally by superposed planes having a rectilinear motion as well as by the planes or carrying surfaces of biplane or multiplane flying machines.

Earlier studies had led experimenters to this conclusion that the efficiency of screw

propellers, and generally of rotating inclined planes as supporting devices, is less than the efficiency of inclined planes having rectilinear motion.

Each experimenter has worked out his own particular efficiency, whereas in the case of inclined planes having rectilinear motion, it has been possible, owing to aeroplanes, to determine an approximately fixed efficiency as regards their action as supporting devices.

The hereinbefore stated reasonings and investigations show that screw propellers and rotating planes have a higher efficiency than they were thought to have even as regards their action as supporting devices.

What I claim is:—

1. In propelling, tractive and supporting apparatus such as screw propellers or inclined planes and the like operating in air and water, the combination upon one shaft of two propellers or inclined planes having different pitches such that the incidence or pitch of the propeller or inclined plane on the exit or exhaust side is 75% greater than the incidence or pitch of the propeller on the suction or admission side. 65

2. In propelling, tractive and supporting apparatus such as screw propellers or inclined planes and the like operating in air and water the combination upon a vertical shaft of two propellers or inclined planes having different pitches such that the incidence or pitch of the propeller or inclined plane on the exit or exhaust side is 75% greater than the incidence or pitch of the propeller on the suction or admission side. 70 75

In testimony whereof I have signed my name to this specification.

TRAJAN VUIA.
